ALARM

Melissa B. Fulton, Chicago, Ill.

Application May 13, 1936, Serial No. 79,536

3 Claims. (Cl. 116—10)

This invention relates in general to signal devices, and more particularly to an alarm mechanism adapted to be mounted on a door.

A principal object of the invention is the provision of an alarm mechanism comprising part of the means for opening and closing a door which may be set to give an audible signal whenever said means is operated.

Another important object of the invention is the provision of such a signal device in which the control and operating mechanism is mounted within one of the door knobs, and said knob is used as a bell.

A further important object of the invention is the provision of such an alarm mechanism in which partial rotation of either of the door knobs will cause relative movement between the bell clapper or striker and a control member therefor to initiate operation of said clapper.

Another object of the invention is the provision of a further control member in such an alarm mechanism which may be manually set to permit operation of said clapper in the above described manner or to disable it entirely.

Numerous other objects and advantages of the invention will be apparent as it is better understood from the following description, which, when taken in connection with the accompanying drawing, discloses a preferred embodiment thereof.

In the drawing,

Figure 1 is a front elevational view of a device embodying the features of the instant invention;

Fig. 2 is a side elevational view taken from the left of Figure 1;

Fig. 3 is a vertical longitudinal sectional view through the alarm mechanism;

Fig. 4 is a vertical sectional view taken substantially on the line 4—4 of Figure 3;

Fig. 5 is a view similar to Figure 4, with the parts moved to operative position;

Fig. 6 is a vertical sectional view taken substantially on the line 6—6 of Figure 5; and

Fig. 7 is a horizontal sectional view taken substantially on the line 1—1 of Figure 4.

Referring more particularly to the drawing, reference numeral 11 indicates a door in which is mounted the conventional locking mechanism 12 and a shaft 13 operatively associated therewith and extending outwardly from either side of the door 11 in the usual manner. A door knob 14 is secured to one end of the shaft 13 by a set screw 15 on the outer side of the door 11. A knob 16 is similarly secured by a set screw 17 to the inner end of the shaft 13. The door

knob 16 comprises a hollow shell having the rearwardly disposed shaft receiving portion 18 formed integrally therewith, and is provided with a circular aperture 19 in its forward wall.

A supporting member 21 is disposed interiorly of the hollow knob 16, and is secured to the rear face thereof by screws 22. The supporting member 21 is provided with a cylindrical hub portion 23 extending forwardly therefrom in substantial axial alignment with the shaft 13 (Fig. 3). The rear one of a pair of frame members 24 is rigidly secured to the hub portion 23 of the supporting member 21, the frame members 24 being secured together and held in parallel relationship by a plurality of spacing members or rods 25. A circular plate member 26 by slightly smaller diameter than the aperture 19 in the forward wall of the knob 16 is secured to the forward frame member 24 by a screw 27. A shaft 28 is rotatably supported by the frame members 24, and has a gear wheel 29 secured thereto intermediate its ends. The shaft portion of a key 31 is rotatably mounted on the inner end of the shaft 28 and extends through the plate 26, the latter forming a bearing therefor.

A suitable spring casing 32 is disposed between 25 the gear 29 and the forward frame member 24, and is secured in any suitable manner to the key 31. One end of a suitable clock spring which is mounted within the casing 32 is secured thereto, the other end of the spring being secured to the 30 gear 29.

Referring to Fig. 4, a ratchet wheel 33 is secured to the shaft portion of the key 31 adjacent the forward frame member 24, and a click pawl or detent 34 is pivotally mounted on the forward frame member 24 adjacent the ratchet wheel 33, and is resiliently urged into engagement with the teeth of the latter by the free end of a C-shaped spring 35, the other end of which is secured at 36 to the forward frame member 24. 40

It will thus be seen that the spring within the casing 32 may be wound up by the key 31, and will be retained in wound condition by the members 33, 34 and 35 in well known manner.

A shaft 37 (Figs. 4 and 5) is rotatably mounted between the frame members 24. Secured to this shaft 37 and to each other are a lantern wheel 38 and an escapement wheel 39. The lantern wheel 38 meshes with the gear 29, and is adapted to be rotated by the latter, which is in turn driven by the spring within the housing 32.

A lever 41 is rotatably mounted adjacent one end on one of the spacer members 25, and has formed integrally therewith a pair of curved ex-

tensions 42 comprising escapement pawls which co-operate with the teeth of the escapement wheel 39. The other end of the lever 41 has a head portion 43 secured thereto. Rotation of the escapement wheel 39 by the clock spring in the manner above described will cause rapid oscillation of the lever 41 in well known manner, the lever with its head 43, comprising a clapper which will thus be repeatedly struck 10 against the inner surface of the hollow door knob 16.

A pin 44 extends through and is slidably mounted within a bearing portion 45 formed integrally with the plate 26, as will be seen from Fig. 7. When the pin 44 is in its innermost position, shown in full lines therein, its inner end engages against the inner edge of the lever 41 to prevent oscillation of the latter. If the pin 44 is pulled outwardly to its dotted line position of Fig. 7, the lever 41 will be free to oscillate under the influence of the clock spring. A cross-pin 46 may be inserted in the pin 44 to limit outward movement of the latter.

A bolt 47 is mounted in the hub portion 23 of the supporting member 21 (Fig. 6). A weight 48 is mounted adjacent its upper end for pivotal movement on the bolt 47. Extending forwardly from the weight 48 adjacent the central portion thereof is a pin 49 which may be secured to the weight in any suitable manner. It will be readily apparent that rotation of the shaft 13 by either of the door knobs 14 or 16 will move the alarm mechanism mounted within the latter relative to the weight 48, since the weight will remain in its position of Figs. 4 and 5 due to the force of gravity.

If the mechanism is in its normal position, as shown in Fig. 4, and the pin 44 is removed from the path of the lever 41, the head portion 43 of the lever will strike against the pin 49 carried by the weight 48. In this manner the clapper is prevented from striking against the bell, comprising the hollow knob 16. Rotational movement of the shaft 13, however, will swing the clapper 45 and its driving mechanism relative to the weight 48 so that the head 43 will not contact the pin 49. Since the pin 44 has been pulled forwardly to its dotted line position of Fig. 7, the clapper will be repeatedly oscillated by the clock spring. In this manner a distinct audible signal or alarm will be given whenever either of the door knobs 14 or 16 is turned in either direction. Normally the usual spring mechanism within the lock 12 will maintain the shaft 13 and the knob 16 in the position of Fig. 4. Consequently, if the pin 44 is moved to its inoperative position, any movement of the knobs 14 or 16 will result in an audible alarm being given. The alarm mechanism may be prevented from operating under any circumstances, however, by pushing the pin 44 to its inner position, in which it will block movement of the clapper.

It is thought that the invention and many of its attendant advantages will be understood from the foregoing description, and it will be appar-

ent that various changes may be made in the form, construction and arrangement of the parts without departing from the spirit and scope of the invention or sacrificing all of its material advantages, the form hereinbefore described being merely a preferred embodiment thereof.

I claim:

1. An alarm mechanism, comprising a housing, a clapper mounted for oscillation within said housing, driving mechanism mounted within said housing for oscillating said clapper and including an escapement wheel and a pawl adapted to be driven thereby and operatively associated with said clapper, and a pendulum mounted in said housing having a pin extending substantially perpendicularly from a face thereof for normally contacting said clapper to prevent oscillation thereof, relative movement between said pendulum and the rest of said mechanism from normal position permitting oscillation of said clapper, and relative movement between said pendulum and the rest of said mechanism back to normal position resulting in said pin again preventing oscillation of said clapper.

2. An alarm mechanism, comprising a housing, a clapper mounted for oscillation within said housing, driving mechanism mounted within said housing for oscillating said clapper and including an escapement wheel and a pawl adapted to be driven thereby and operatively associated with said clapper, a pendulum mounted in said housing having a pin extending substantially perpendicularly from a face thereof for normally contacting said clapper to prevent oscillation thereof, relative movement between said pendulum and the rest of said mechanism from normal position permitting oscillation of said clapper, and relative movement between said pendulum and the rest of said mechanism back to normal position resulting in said pin again preventing oscillation of said clapper, and means selectively operable to prevent oscillation of said clapper at all times.

3. An alarm mechanism, comprising a hollow door knob, a supporting frame mounted within said door knob in spaced relationship to the inner sides of the walls of the knob, a clapper mounted on said frame, driving mechanism mounted on said frame for oscillating said clapper and including an escapement wheel and a pawl adapted to be driven thereby and operatively associated with said clapper, a pendulum mounted within said door knob having a pin extending substantially perpendicularly from a face thereof for normally engaging said clapper to restrain the same against oscillation, rotative movement of said door knob moving said clapper out of engagement with said pendulum to allow said driving mechanism to oscillate the latter into and out of engagement with said door knob to give an audible alarm, and means selectively operable to prevent oscillation of said clapper at all times.

MELISSA B. FULTON.
